(57) **CLAIM**

We claim the ornamental design for a wine glass hanger, as shown and described.

DESCRIPTION

FIG. 1 is a front perspective view of a wine glass hanger showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is an enlarged view of the encircled portion of the wine glass hanger shown in FIG. 1;
FIG. 9 is an enlarged view of the encircled portion of the wine glass hanger shown in FIG. 2;
FIG. 10 is an enlarged view of the encircled portion of the wine glass hanger shown in FIG. 6;
FIG. 11 is a left-side cross-sectional view of the claimed portion of the wine glass hanger shown in FIG. 2; and,
FIG. 12 is a right-side cross-sectional view of the claimed portion of the wine glass hanger shown in FIG. 2.
The broken lines in the figures show portions of the wine glass hanger which form no part of the claimed design.
The dot-dash broken lines encircling portions of the claimed design that are illustrated in enlargements form no part of the claimed design.

1 Claim, 8 Drawing Sheets
